UNITED STATES PATENT OFFICE.

ROCCO CENTRONE, OF BROOKLYN, NEW YORK, ASSIGNOR OF ONE-HALF TO FRANK NAPOLI, OF BROOKLYN, NEW YORK.

DESIGN FOR A SHOE VAMP.

Application filed December 16, 1922. Serial No. 4,622. Term of patent 3½ years.

To all whom it may concern:

Be it known that I, Rocco CENTRONE, a citizen of the United States, residing at Brooklyn, in the county of Kings and State of New York, have invented a new, original, and ornamental Design for Shoe Vamp, (Case A), of which the following is a specification, reference being had to the accompanying drawing, forming part thereof.

In the drawings:—

The figure is a plan view of the shoe vamp.

I claim:—

The ornamental design for a shoe vamp, as shown.

ROCCO CENTRONE.
